Attorney

UNITED STATES PATENT OFFICE.

HENRY G. KRASKY, OF BERKELEY, CALIFORNIA.

GRAINING-MACHINE.

No. 839,895.

Specification of Letters Patent.

Patented Dec. 25, 1906.

Application filed July 10, 1906. Serial No. 325,552.

To all whom it may concern:

Be it known that I, HENRY G. KRASKY, a citizen of the United States, residing at Berkeley, in the county of Alameda and State of California, have invented certain new and useful Improvements in Graining-Machines; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to new and useful improvements in apparatus for graining surfaces, and comprises a simple and efficient device of this nature consisting of a suitable frame having a composition roller with a feed-roller resting thereon, and in the provision of a graining-roller provided with removable strips upon which the designs to be transferred are held and adapted to be adjustably held, so as to contact with the composition roller as the two rollers rotate toward each other.

The invention consists, further, in various details of construction and combinations and arrangements of parts which will be hereinafter fully described and then specifically defined in the appended claim.

I illustrate my invention in the accompanying drawings, in which—

Figure 1 is a vertical sectional view 35 through the frame of my apparatus, showing the graining and impression rollers in elevation. Fig. 2 is a top plan view, and Fig. 3 is a sectional view through the graining-roller.

Reference now being had to the details of 40 the drawings by letter, A designates the frame of the apparatus, upon which are mounted the bearings B, in which a shaft C is journaled, which shaft has a pinion-wheel C' fixed thereto, adapted to mesh with a worm 45 D, rotating with the shaft D', mounted in suitable bearings upon the frame.

F designates a second shaft journaled in bearings F', which are adjustably held upon the frame, and G is a pinion-wheel fixed to 50 the shaft F and adapted to mesh with a worm G', also fixed to the shaft D'. It will be noted that said worms are so formed with right and left threads that the two cylinders I and K, rotating, respectively, with said 55 shafts, will be caused to rotate toward each other in the direction of the arrows. Said

roller or cylinder I has a coating of a composition material about its circumference and rotates in contact with the circumference of the design roller or cylinder K, upon which 60 the design is formed. Said cylinder K has annular slotted ends and is held to the ends of the cylinder K by means of the flanges O, projecting from the inner surface.

Directly underneath the cylinder K, which 65 has the flanges O, is an ink-tank Q, in which said cylinder rotates, and Q' designates a wiper pivoted to the frame and has a rod R fixed thereto, and a portion of said rod has threads adapted to receive the adjusting- 70 wheel R'.

Directly underneath the cylinder I is a tank T, in which the cylinder I rotates for the purpose of washing off the ink thereon, and T' is a scraper which has a rod T² fixed there- 75 to and an adjusting-wheel T³ fitted upon the threaded part thereof.

A feeding-roller W is journaled upon the arms W', which are pivoted at their rear ends to the frame, and said roller is adapted to 80 ride upon the composition cylinder, whereby the object upon the surface of which the design is to be transferred may be held.

From the foregoing it will be noted that by 85 the provision of the apparatus shown and described a simple and efficient means is afforded for transferring designs of various kinds first from the design-cylinder to the composition surface of the cylinder I, thence to any surface which may be held in contact 90 with the rotating cylinder.

What I claim is—

A graining-machine comprising a frame, a hollow cylinder adapted to bear a design and having an annular groove in each end, the 95 outer wall of each groove projecting beyond the inner wall of the groove, cylinder-heads each provided with two concentric circular flanges with a space between the same adapted to receive the portion of the cylinder intermediate said grooves and the inner circumference of the cylinder, the outer faces of said ends and the ends of said cylinder being flush, and rods passing through said ends and adapted to hold the same in engagement 100 with the cylinder, as set forth.

In testimony whereof I hereunto affix my signature in the presence of two witnesses.

HENRY G. KRASKY.
